Edgar Galt

UNITED STATES PATENT OFFICE.

ISAAC BERTIN, OF NEW YORK, N. Y.

SHOPPING BAG.

Application filed December 2, 1920. Serial No. 427,719.

To all whom it may concern:

Be it known that I, ISAAC BERTIN, a citizen of the United States, and residing at New York, in the county of New York and 5 State of New York, have invented certain new and useful Improvements in Shopping Bags, of which the following is a specification, such as will enable those skilled in the art to which it appertains to make and 10 use the same.

This invention relates to what are known as shopping bags which are usually made of paper or other suitable fibrous material, and the tops of which are open and provided 15 with loop-shaped handles also composed of fibrous material, and the invention described and claimed herein relates particularly to the construction or formation of the handles and the method of applying them to the top 20 of the opposite side portions of the bag and securing them therein.

The invention is fully disclosed in the following specification, of which the accompanying drawing forms a part, in which 25 the separate parts of my improvement are designated by suitable reference characters in each of the views, and in which:—

Fig. 1 is a side view of a shopping bag and showing one side of the top thereof 30 provided with one of my improved handles, and part of the construction being broken away;

Fig. 2 a similar view showing the method of forming a handle and of attaching it 35 to the top of one side portion of a bag;

Fig. 3 a section on the line 3—3 of Fig. 2 but showing only one side portion of the bag;

Fig. 4 a view of one of my improved 40 handle loop members complete and ready to be attached;

Fig. 5 an inside view of the top of one side portion of the bag and showing one step in the process of attaching a handle; and, 45

Fig. 6 a view similar to Fig. 3 but showing a modification.

In Fig. 1 of the accompanying drawing I have shown at a an ordinary shopping bag which is composed of strong paper or other 50 suitable material and which is open at the top, and said top of the bag is also provided with an inwardly folded rim member a^2 , which extends entirely around the top of the bag and gives form and strength there- 55 to, and said rim member, at the opposite

sides of the bag, at the top thereof, is slotted transversely, at predetermined points, as shown at a^3 to form from said rim member supplemental folding flaps or tongues a^4 , and at the point where the opposite ends 60 of the flaps or tongues a^4 join the body of the sides of the bag are formed circular apertures or recesses a^5 , as clearly shown in Fig. 5.

In the practice of my invention I provide 65 handle loop members b , one of which is shown in each of the Figures 1 to 4 inclusive, and in Fig. 6, and these handle loop members are composed of twisted, braided, woven or otherwise formed ropes, cords or 70 straps of fibrous material which are cut of the desired length, after which the ends thereof are unbraided, or untwisted and formed into fan-shaped terminals b^2 , one of which is shown in full lines and the other 75 in dotted lines in Fig. 2.

I also provide oblong straps c of heavy 80 strong paper or similar material to which the fan-shaped terminals b^2 of the handle loop members b are sealed, pasted or otherwise secured and, in the construction shown in Figs. 1 to 4 inclusive, two of the straps c are employed, the terminals b^2 of the handle loop members being first secured to one of said straps after which the other 85 strap is secured to the first named strap by pasting, gluing, sealing or otherwise so as to enclose the fan-shaped terminals b^2 of the handle loop members.

The straps c constitute the attaching 90 means for the handle loop members and in connecting a handle loop member with the top of one side of the bag, the flap or tongue a^4 is opened as shown in Fig. 5, after which the handle attaching strap member c of the 95 handle loop member is placed in position with its ends under the adjacent ends of the rim member a^2 , after which the flap or tongue member a^4 is folded inwardly over the handle attaching strap member c as 100 shown in Figs. 1 and 3, and in this operation the handle attaching strap member c which consists of two parts in the construction shown in Figs. 2, 3 and 4, is sealed to the side of the bag and the flap or tongue 105 a^4 is sealed to the handle attaching strap member and the end portions of the rim a^2 are also sealed to the side of the bag and to the front of the handle attaching strap member c , and when the handle has thus been 110

attached the sides of the loop member of the handle pass through the apertures or holes α^s .

This forms a neat and finished appearance for the top of the bag and a handle made and applied in the manner described cannot be pulled out without tearing the top of the bag to pieces or destroying it, and it will be understood, of course, that a handle is applied to both sides of the top of the bag in the manner described.

In Fig. 6 of the drawing, I have shown a modification in which only one handle attaching strap member c is employed, and the fan-shaped terminals of the handle loop member are secured to this strap member and the complete handle is secured in the bag in the same manner as hereinbefore described when two of said strap members are employed.

From the foregoing description it will be seen that my improved handle members consist, as a matter of fact, of the loop members and of the strap members connected therewith, the strap members forming the means by which the loop members are secured to the bag, and it will be understood that my invention is not limited to any particular material in the construction of the bag or any particular material in the construction of the handle loop member, nor of the attaching strap members with which the loop members are provided, and various changes in and modifications of the construction herein described may be made, within the scope of the appended claims, without departing from the spirit of my invention or sacrificing its advantages.

Having fully described my invention, what I claim as new and desire to secure by Letters Patent, is:—

1. A handle device for paper or other fibrous bags, the top of which is open and provided with an inwardly folded rim which is cut transversely to form a supplemental flap or tongue, and a loop-shaped handle device composed of woven, twisted, braided or

other fibrous material and the ends of which are expanded into fan-shaped form and sealed to a transverse handle attaching strap, 50 said strap being placed under said flap or tongue member which is folded inwardly thereover and sealed thereto.

2. A handle device for paper or other fibrous bags, the top of which is open and 55 provided with an inwardly folded rim which is cut transversely to form a supplemental flap or tongue, and a loop-shaped handle device composed of woven, twisted, braided or other fibrous material and the ends of which are expanded into fan-shaped form and 60 sealed to a transverse handle attaching strap, said strap being placed under said flap or tongue member which is folded inwardly thereover and sealed thereto, as are also 65 parts of the inwardly folded rim at the top of the bag.

3. A handle device for paper bags open at the top and provided with an inwardly folded rim which is cut transversely to 70 form a supplemental flap or tongue, and a loop-shaped handle device the ends of which are flared and secured to a transverse handle attaching strap, said strap being placed under said flap or tongue which is folded 75 inwardly thereover and sealed thereto for securing said handle device to said bag.

4. A handle device for bags of the class specified open at the top and provided with an inwardly folded rim cut transversely to 80 form a supplemental flap or tongue and loop-shaped handle devices the ends of which are flared and secured to the bag inwardly of said inwardly folded rim and said supplemental flap or tongue. 85

In testimony that I claim the foregoing as my invention I have signed my name in presence of the subscribing witnesses this 30th day of November, 1920.

ISAAC BERTIN.
